UNITED STATES PATENT OFFICE.

ALMA A. ROSE, OF NEW YORK, N. Y.

DESIGN FOR A PALETTE FOR CHINA-PAINTING.

SPECIFICATION forming part of Design No. 30,172, dated February 14, 1899.

Application filed January 21, 1899. Serial No. 702,991. Term of patent 7 years.

To all whom it may concern:

Be it known that I, ALMA A. ROSE, a citizen of the United States, residing at New York, in the borough of Brooklyn and State of New 5 York, have invented and produced a new and original Design for Palettes for China-Painting, of which the following is a specification.

This invention relates to a design for palettes for china-painting, which is illustrated 10 in the accompanying drawing, in which a palette made according to my design is represented in a perspective view.

As shown in the drawing, the leading feature of my design consists of two rectangular 15 frames or ribs a b, arranged side by side in one of the corners of a larger rectangular frame A, which surrounds the palette P proper. The smaller corner-frames are oblong and are arranged parallel with each other.

What I claim as new is—

The design for a palette for china-painting, as herein shown and described.

In testimony that I claim the foregoing as my invention I have signed my name in presence of two subscribing witnesses.

25 ALMA A. ROSE.
